W. H. FREER

LAVATORY STOPPER

Filed Feb. 5, 1925

*W. H. Freer,
Inventor*

*By Clarence A. O'Brien
Attorney*

UNITED STATES PATENT OFFICE.

WINSTON HENRY FREER, OF ST. ALBANS, VERMONT.

LAVATORY STOPPER.

Application filed February 5, 1925. Serial No. 7,073.

To all whom it may concern:

Be it known that I, WINSTON H. FREER, a citizen of the United States, residing at St. Albans, in the county of Franklin and State of Vermont, have invented certain new and useful Improvements in a Lavatory Stopper, of which the following is a specification.

This invention relates to improvements in stoppers for use particularly in connection with the waste outlet or drain of a lavatory, and has for its principal object to provide a means for preventing an overflow.

One of the important objects of the present invention is to provide a stopper of the above mentioned character, wherein means is associated therewith for automatically allowing the water in the wash basin to be discharged outwardly into the waste outlet upon the water reaching a predetermined level in the basin.

A still further object is to provide a stopper of the above mentioned character, which includes an auxiliary stopper, said auxiliary stopper being adapted to normally close the opening in the main stopper for preventing the water from being emptied from the lavatory, said auxiliary stopper being automatically adapted to be moved out of engagement with the opening when the water in the lavatory reaches a predetermined level so as to permit any surplus water to be discharged out through the waste outlet thereby preventing any overflow in the lavatory.

A still further object is to provide a stopper of the above mentioned character, which is simple in construction, inexpensive, strong and durable and further well adapted for the purposes designed.

Other objects and advantages of this invention will become apparent during the course of the following description.

In the accompanying drawing, forming a part of this specification, and in which like numerals designate like parts throughout the same:

The figure represents a view partly in section, and partly in elevation of the stopper embodying my invention.

In the drawing, wherein for the purpose of illustration is shown the preferred embodiment of my invention, the numeral 1 designates a stopper which is of a conventional construction, the same being adapted to be removably inserted in the usual waste

outlet or drain provided in the bottom of a wash basin. A centrally located opening 2 is formed in the bottom of the stopper and diverging upwardly therefrom through the top of the stopper are passages 3 and 4. The purpose thereof will be hereinafter more fully described.

Forming a closure for the central opening 2 is the plate or disc 5, the same being adapted for engagement with the bottom of the stopper 1 in the manner as clearly illustrated in the drawing. Extending centrally in the upper portion of the stopper 1 is the bolt 6, the head 7 thereof adapted to support the ring 8, the purpose of which is to provide a means for inserting and removing the stopper for the purpose well known in the art. The threaded end 9 of the bolt extends downwardly into the intermediate portion of the stopper at the point of intersection of the upwardly converging passages 3 and 4. A nut 10 is threaded on the lower threaded end of the bolt and is operable within a suitable cut out portion 11 provided therefor in the upper portion of the stopper.

An upwardly extending lug 12 is formed on the central portion of the plate 5. A coil spring 13 is secured at its lower end to said lug, and at its upper end to said nut 10. The purpose of the coil spring 13 is to normally hold the plate 5 in engagement with the bottom of the stopper 1 whereby the opening 2 is normally closed. The tension of the coil spring 13 is regulated by rotating the bolt 6 through the medium of the ring 8 causing the nut 10 to be moved along the threaded portion 9 of the bolt in the manner as is obvious from the construction illustrated.

When the stopper 1 is in the usual waste outlet provided in the bottom of a wash basin, the latter is filled with water in the usual manner. Upon the water reaching a predetermined height or level in the basin, the weight of the water will exert a downward pressure on the plate 5 causing the same to move downwardly away from the bottom of the stopper and uncovering the opening 2. This permits any excess water to flow through the passages 3 and 4, and through the opening 2 into the waste outlet pipe so that the wash basin will not overflow. After the surplus water has been discharged from the wash basin, the coil spring 13 will return the plate 5 to its normal po-

sition closing the opening 2 and preventing the water in the basin from being emptied or discharged therefrom. The stopper 1 is adapted to be removed from the waste outlet in the usual manner in order to discharge the water from the lavatory.

The simplicity in which my improved stopper is constructed, enables the tension of the spring to be regulated in such a manner as to control the actuation of the plate so that the latter may be caused to operate at any desired level reached by the water in the lavatory. Furthermore, a stopper of the above mentioned character, will at all times be positive and efficient in its operation as well as automatic and will prevent any possibility of an overflow which often results by the use of the ordinary stoppers. A stopper of the above mentioned character may be manufactured at a very low cost.

While I have shown the preferred embodiment of my invention, it is to be understood that various changes in the sizes, shape and arrangement of parts may be resorted to without departing from the spirit of the invention and scope of the appended claims.

Having thus described the invention, what I claim is:—

1. In a stopper for a lavatory, said stopper being provided with a water outlet opening, a closure plate for said outlet opening, means for normally holding the closure plate against the bottom of the stopper for preventing the flow of water through the

outlet opening, said closure plate adapted to be moved into an inoperative position whereby the outlet opening is uncovered when the water in the lavatory reaches a predetermined level to permit the flow of the excess water through said outlet.

2. In a stopper for a lavatory, the same being provided with an outlet opening, a valve for said outlet opening, means for normally holding the same in a closed position, said valve adapted to be opened when the water in the lavatory reaches a predetermined level to permit the flow of the excess water outwardly through the water outlet opening, said means comprising a coil spring secured at one end to said valve and at its opposite end to the usual ring securing means associated with the stopper.

3. In a stopper for a lavatory, the same being provided with an outlet opening, a valve for said outlet opening, means for normally holding the same in a closed position, said valve adapted to be opened when the water in the lavatory reaches a predetermined level to permit the flow of the excess water outwardly through the water outlet opening, said means comprising a coil spring secured at one end to said valve and at its opposite end to the usual ring securing means associated with the stopper, and means for adjusting the tension of said coil spring.

In testimony whereof I affix my signature.

WINSTON HENRY FREER.
